DESIGN FOR A PLURAL-NOTE WHISTLE

Irwin E. Cohn, Leominster, Mass.

Application January 22, 1942, Serial No. 105,355

Term of patent 7 years

To all whom it may concern:

Be it known that I, Irwin E. Cohn, a citizen of the United States, residing in Leominster, county of Worcester, State of Massachusetts, have invented a new, original, and ornamental Design for a Plural-Note Whistle, of which the following is a specification, reference being had to the accompanying drawing, forming part thereof:

Figure 1 is to top plan view of a plural-note whistle, showing my new design.

Figure 2 is a front end elevation of the same.

I claim:

The ornamental design for a plural-note whistle, as shown.

IRWIN E. COHN.
